REFINING MINERAL OILS

George R. Gilbert, Baytown, Tex., assignor to
Standard Oil Development Company, a corpora-
tion of Delaware

Application July 5, 1941, Serial No. 401,067

11 Claims. (Cl. 196—33)

The present invention is concerned with the refining of mineral oils. The invention more particularly relates to an improved process for the removal of objectionable sulfur compounds from petroleum oils, particularly from petroleum oils boiling in the motor fuel and heating oil boiling ranges. In accordance with the present process objectionable sulfur compounds as, for example, mercaptans are removed from petroleum oils containing the same by treating the oil with an alkali metal plumbite solution under conditions to form oil-soluble, preferably basic lead mercaptides. The oil containing the lead mercaptides is then distilled under conditions adapted to remove overhead a distillate free of mercaptan and lead compounds. The bottoms fraction containing the soluble lead mercaptides is treated in a manner to separate the lead which is usually accomplished by the addition of free sulfur or an equivalent means.

It is known in the art to refine petroleum oils by various distillation, cracking and related operations. For example, it is known to remove objectionable sulfur compounds from petroleum oils boiling in the motor fuel and heating oil boiling ranges utilizing various procedures. One operation comprises contacting the oil with a mineral acid, as, for example, sulfuric acid under conditions to remove the sulfur compounds and other objectionable constituents. This process, however, is not entirely satisfactory, since the acid, such as sulfuric acid, also tends to remove desirable constituents which have relatively high octane numbers. Another conventional operation employed for the removal of mercaptan compounds is to contact the oil with a so-called "doctor solution" which comprises a sodium plumbite solution. The sodium plumbite solution is generally prepared by saturating a 10° to 30° Baumé sodium hydroxide solution with lead oxide.

In this latter operation the mercaptans dissolved in the oil react with the sodium plumbite under conditions to form oil-soluble neutral lead mercaptides. The spent doctor solution is separated and the oil is then treated in a manner to remove therefrom the soluble lead compounds. This is accomplished by a number of procedures, such as by oxidation, by means of hydrogen peroxide, and the like. However, the conventional method is to add free sulfur under conditions to precipitate the lead as lead sulfide and to form the corresponding alkyl disulfides. The precipitated lead sulfide is removed from the oil which contains dissolved therein relatively innocuous

alkyl disulfides. This operation, however, possesses several disadvantages, one of which is that the precipitated lead sulfide is flocculent and rather difficult to remove from the treated oil. Another disadvantage is that it is desirable to add the theoretical amount of sulfur to the oil in order to precipitate the total quantity of lead as lead sulfide. If an insufficient amount of sulfur be added, all the lead compounds are not removed from the oil which results in the production of an inferior product having relatively poor properties. On the other hand, if an excess of sulfur be added, the excess sulfur remains dissolved in the oil which materially increases the corrosiveness of the oil. Furthermore, the excess sulfur dissolved in the oil substantially decreases the susceptibility of the oil toward knock-suppressing agents, such as tetraethyl lead and the like. However, when adding the theoretical correct amount of sulfur, the reaction proceeds rather slowly and the capacity of the sweetening equipment must be relatively large.

In order to overcome the disadvantages of these procedures, various alternate procedures have been suggested. For example, it has been suggested that a distillation stage be employed in conjunction with the conventional doctor treating process. However, an operation of this character is not satisfactory due to the fact that when the oil containing the alkyl disulfides is distilled, the disulfides tend to decompose. The sulfur compounds are removed overhead with the oil, resulting in the production of a product which is not satisfactory. It has also been proposed to distill the doctor-washed oil while injecting steam into the still. This operation has not been successful, since the lead mercaptides tend to hydrolyze in the presence of steam and an oil which is not sweet to the doctor test is recovered overhead.

I have, however, now discovered that providing the oil be contacted with a doctor solution in an initial stage under specific conditions and then distilled in a secondary stage under restricted conditions, it is possible to remove overhead from the secondary stage a sweet distillate which may be employed as a motor fuel. The process of my invention may be readily understood by reference to the attached drawing illustrating embodiments of the same. Figure 1 illustrates a process wherein in the total fraction boiling in the motor fuel boiling range is doctor treated, while Figure 2 illustrates a preferred adaptation of the invention wherein the lighter boiling constituents by-pass the doctor treating stage.

Referring specifically to Figure 1, it is assumed that the feed oil is a crude petroleum oil. It is also assumed that it is desired to produce a sweetened product having a final boiling point in the range from about 400 to 425° F. The feed oil is introduced into distillation zone 1 by means of feed line 2. Temperature and pressure conditions are adjusted in zone 1 adapted to remove overhead by means of line 3 constituents having a final boiling point in the range from about 450 to about 475° F. and to remove by means of line 4 constituents boiling above this range. The vaporous product removed by means of line 3 is condensed in zone 5 and introduced into separation zone 6 wherein uncondensed constituents are separated from the condensate and removed overhead by means of line 7. The condensate having a final boiling point in the range from about 450 to 475° F. is mixed with a quantity of doctor solution which is withdrawn from doctor storage 9 and introduced into line 8 by means of line 10. The amount of doctor solution added is adjusted so that the mercaptans completely react with the doctor solution to form basic lead mercaptides. This is accomplished by utilizing an appreciable excess of doctor solution as compared to the oil. For the purpose of description it is assumed that 10 volumes of 20° Baumé caustic solution saturated with lead oxide is used per volume of oil.

The mixture is passed through mixing zone 11 and introduced into separation zone 22. In separation zone 22 the spent plumbite solution is separated from the lead-containing oil and is removed by means of line 23. The treated oil is removed from separation zone 22 by means of line 24 and introduced into distillation zone 12.

Temperature and pressure conditions are adjusted in zone 12 so as to remove overhead by means of line 13 a vaporous product substantially completely free of mercaptan compounds and other objectionable sulfur compounds. For purposes of illustration it is assumed that temperature and pressure conditions in zone 12 are adjusted to remove overhead by means of line 13 a vaporous product having a final boiling point in the range from about 400 to about 425° F. The vaporous product removed overhead is passed through condensing zone 14 and introduced into separation zone 15 wherein the uncondensed constituents are separated from the condensate and removed by means of line 16. The condensate is removed by means of line 17 and further refined and handled as desired. The bottoms are removed from distillation zone 12 by means of line 18 and passed into treating zone 19 wherein the lead mercaptides are treated in a manner to precipitate the lead. This is preferably accomplished by means of sulfur which is introduced by means of line 20. The lead sulfide is removed by means of line 21, combined with the spent doctor solution withdrawn from zone 22 by means of line 23 and the mixture passed to regeneration zone 24 wherein the same is treated and recycled to storage zone 9. The spent doctor solution is regenerated by separating entrained hydrocarbon from it by any suitable means, such as by centrifuging, and then blowing the solution with an oxygen-containing gas, such as air. Additional caustic or lead oxide may be added to replace alkali and lead which may have been removed during the treating operation.

Referring specifically to Figure 2 which illustrates a preferred adaptation of the present invention, the condensate removed from separation zone 6 by means of line 8 is introduced into a

distillation zone 30 rather than directly into the doctor treating stage as illustrated in Figure 1. Temperature and pressure conditions are adjusted in distillation zone 30 to remove overhead by means of line 31 the relatively lower boiling hydrocarbon constituents. The relatively higher boiling hydrocarbon constituents are removed from zone 30 by means of line 32 and mixed with a doctor solution which is introduced by means of line 10. The mixture is passed through doctor treating zone 11 and handled as described with respect to Figure 1, except that the overhead removed from distillation zone 12 is preferably combined with the overhead removed from zone 30. However, under certain conditions the overhead removed from zone 30 may be removed from the system by means of line 33. When operating as described with respect to Figure 2, the amount removed overhead from distillation zone 30 may vary considerably but generally comprises from about 20% to 60% of the total feed to the distillation zone.

The process of the present invention may be widely varied. It is to be understood that the respective zones may comprise any suitable number and arrangement of units. The process may be readily adapted for the removal of mercaptan compounds from any feed oil containing the same. It is, however, particularly adapted for the removal of mercaptan compounds from petroleum oils boiling in the range from about 100° F. to about 650° F., particularly from oils boiling in the motor fuel boiling range from about 100° F. to about 420° F. The feed oil may be secured from an initial distillation operation or may be secured from thermal cracking operations, from catalytic cracking operations or from various alkylation and isomerization operations.

Although the feed oil to the doctor treating zone may boil in the range of the boiling range desired in the final refined product, in general, it is preferred that the feed oil entering the treating zone have a final boiling point at least 5° F., preferably from 25° F. to 50° F. above the final boiling point desired in the final refined product.

Although any alkali metal plumbite solution may be employed, in general, it is preferred that the solution comprise a sodium plumbite solution which is prepared by saturating a 10° to 30° Baumé sodium hydroxide solution with lead oxide. The amount of doctor solution employed is sufficient so that the mercaptan compounds present in the feed oil will be converted to lead mercaptides, preferably to the basic lead mercaptides.

The doctor treated oil containing dissolved therein the soluble basic lead mercaptides is distilled under conditions to remove overhead an essentially mercaptan-free oil and to remove as a bottoms a relatively small stream containing the lead mercaptides. In general, the oil is distilled in a vacuum, the pressure of which is in the range from less than 1 inch mercury absolute pressure to about atmospheric pressure. When treating oils boiling in the range from about 100° F. to about 450° F., the vacuum conditions are adjusted so that the temperature in the bottom of the distillation zone does not exceed about 250° F. and preferably is less than about 200° F., in the range from about 150° F. to 175° F. When higher boiling oils, such as kerosene fractions, are being treated in accordance with my invention, it may be necessary to employ a still temperature of about 315° F. in distilling the oil. It is to be understood that different conditions will be re-

quired for different oils. Thus, higher distillation temperatures will be required when kerosene or heating oils are being treated by my process than are needed for oils boiling in the gasoline boiling range. However, the distillation conditions are to be so adjusted by application of vacuum so that decomposition of lead mercaptides is at a minimum.

The oil stream removed from the bottom of the distillation zone may be treated by any suitable means such as with hydrogen peroxide and the like in a manner to remove the lead compounds therefrom. The stream likewise may be treated with an excess amount of sulfur in order to secure a rapid precipitation of the lead sulfide, since the relatively high boiling oil may be readily incorporated in fuel oils rather than employed in motor fuels. However, if desired, this relatively small quantity of oil may be treated with the correct amount of sulfur and a mercaptan-free and lead-free oil removed by means of line 25 and combined with the oil removed from zone 15 by means of line 26. Other adaptations of the present process may be employed. For example, the process may be readily adapted for the recovery of mercaptans from the oil containing a high concentration of mercaptides by treating the same with a mineral acid. Furthermore, the leaded oil may be employed for the production of lead carbonate by blowing the same with carbon dioxide.

In order to further illustrate my invention the following examples are given which should not be construed as limiting the same in any manner whatsoever.

Example 1

Mercaptan-containing oils having a final boiling point of about 375° F. and about 400° F. were blended and the blend treated with a 50% excess by volume of doctor solution under conditions to form basic lead mercaptides. The doctor treated oil was distilled under vacuum conditions taking 10% cuts overhead. The distillation operation was conducted under conditions wherein no steam was added during the time the first 10% cut was taken overhead. Steam was employed in removing overhead the remaining 10% cuts. The first 10% cut was substantially free of sulfur compounds while the remaining cuts contained sulfur compounds.

A second portion of the doctor treated oil was rerun without the addition of steam, and with the application of sufficient vacuum to maintain a bottoms temperature not exceeding 190° F. The first 0 to 10% fraction was removed under atmospheric pressure. All fractions, up to 99% overhead, were sweet to the doctor test. The composite overhead condensate had a zero reactive sulfur test. No degradation in color was observed. The remaining 1% bottoms were also found to be doctor sweet and contained some heavy, dark sediment.

An operation similar to that described was conducted except that the mercaptan-containing feed oil was not treated with a doctor solution. Only the initial 0 to 35% overhead cut was found to be doctor sweet.

From the above it is apparent that a finished product freed to the desired extent of objectionable sulfur compounds may be readily produced by doctor treating the feed oil, followed by distilling the doctor treated oil under vacuum conditions in the absence of steam, wherein the temperature at the bottom of the distillation zone is maintained below about 200° F.

Example 2

5 A petroleum oil boiling in the kerosene boiling range, containing 36 mg. of mercaptan sulfur per hundred ml. of oil and having a total sulfur content of 0.13 per cent by weight was distilled under a maximum vacuum of 25 inches of mercury without the use of steam. The temperature at the bottom of the distillation zone did not exceed about 315° F., and a fraction comprising 0 to 95% of the feed oil was removed overhead. On testing this 95 per cent overhead fraction for mercaptan sulfur content, it was found to contain 33 mg. per hundred ml. of oil. The total sulfur content of this fraction was 0.115 per cent by weight.

20 Another portion of this kerosene feed was treated with a doctor solution in an amount so that about 44.5 per cent of the total lead mercaptides formed in the oil were basic mercaptides. The leaded oil was distilled under a vacuum of 25 inches of mercury (maximum) and at a maximum bottoms temperature of about 315° F. No steam was employed during the distillation. A fraction corresponding to 25 95 per cent of the treated oil was taken overhead. This fraction had a mercaptan sulfur content of only 0.6 and a total sulfur content of only 0.075 per cent by weight.

30 A portion of the 5 per cent bottom fraction was washed with a dilute aqueous hydrochloric acid solution (of approximately 5 per cent by weight strength) to regenerate the mercaptan. The oil was washed free from acid with water. On testing the bottoms fraction it was found to have a mercaptan sulfur content of 544 mg. per 35 100 ml. of oil.

Example 3

40 Another portion of the kerosene stock having a mercaptan sulfur content of 36 mg. per 100 ml. was treated with doctor solution in sufficient quantity so that 83.5 per cent of the total lead mercaptides in the oil were in the 45 basic form rather than as neutral mercaptides. The leaded oil was distilled under a maximum vacuum of 25 inches of mercury without employment of steam and a 95.6 per cent fraction was taken overhead at a maximum bottoms temperature of 315° F. On testing this 95.6 per 50 cent fraction, it was found to be sweet to the doctor test and contained only 0.077 per cent by weight of total sulfur.

55 It is apparent that when distilling a leaded oil under vacuum and employing steam very little if any reduction in either mercaptan or total sulfur content is effected. On the other hand, when the oil is leaded and distilled under vacuum without the use of steam substantially all of the oil can be distilled overhead to obtain 60 a product sweet to the doctor test and having a mercaptan sulfur and total sulfur content appreciably lower than that obtained when distilling under vacuum and employing steam. It will be further observed that when the oil is leaded with a sufficient amount of doctor solution so that the mercaptides formed are substantially in the basic form, the reduction in mercaptan sulfur and total sulfur content is appreciably greater and that these compounds may be substantially completely removed from the oil.

65 A further advantage of this method of treating oil is that the mercaptans are concentrated in the bottoms fractions, which fractions cor-

respond to only a small percentage of the original treated oil. These mercaptides which are concentrated in the bottom fractions may be recovered and used for various purposes. For example, the lead mercaptides in the bottom fractions may be treated with an aqueous dilute mineral acid, such as hydrochloric acid or sulfuric acid, whereby the lead salt is precipitated out of the solution and the mercaptans are left in a concentrated form in the hydrocarbon fraction.

Example 4

In order to determine whether the lead might be recovered for further use such as in the paint industry or in the wood preserving industry, a portion of the lead mercaptide concentrate was acidified by contacting it with carbonic acid gas. A precipitate of $PbCO_3$ was thus obtained, which after thorough washing with a hydrocarbon fraction (boiling between 200 and 400° F.) was of a white color. Such a material is useful as a pigment in the paint industry. When it is desired to convert the lead mercaptide to alkyl disulfide, sulfur is employed rather than carbonic acid gas.

Example 5

A portion of the lead mercaptide concentrate was mixed with a slight excess of elementary sulfur and a concentrate of alkyl disulfides was obtained.

Example 6

A high octane cracked naphtha boiling in the motor fuel boiling range which had a mercaptan sulfur content of 21 mg. per 100 ml. of oil and a total sulfur content of 0.091 per cent by weight was distilled under a maximum vacuum of 25 inches of mercury at a maximum bottoms temperature of 250° F. without employing steam to obtain a 0 to 96.5 per cent overhead fraction. On testing this fraction for sulfur content it was found to contain 11 mg. of mercaptan sulfur per 100 ml. and a total sulfur content of 0.068 per cent by weight.

A second portion of the charge stock having a mercaptan sulfur content of 21 mg. per 100 ml. of oil was treated with an amount of doctor solution to form basic lead mercaptides. The oil was then distilled under a maximum vacuum of 25 inches of mercury and a maximum temperature of 250° F. without employing steam to obtain a 96.5 per cent overhead fraction. This overhead fraction was tested for sulfur content and was found to contain 1.5 mg. of mercaptan sulfur per 100 ml. of oil and 0.057 per cent by weight of total sulfur.

A third portion of the sour charge stock was doctor sweetened and the lead mercaptides formed in the oil were broken out using a slight excess of the theoretical quantity of the sulfur. The resultant sweet stock was distilled under vacuum (25 inches of mercury) at a maximum bottoms temperature of 250° F. without employing steam to obtain a 0 to 96.5 per cent overhead fraction. This fraction gave a positive reaction to the doctor test and was found to contain less than 1 mg. of mercaptan sulfur per 100 ml. of oil; the total sulfur was 0.063 per cent by weight.

From the above it is apparent that when practicing my invention, a product of appreciably lower mercaptan sulfur and total sulfur content may be obtained even though the oil is not sweetened prior to distillation as long as the

critical conditions of distillation that I have specified are employed.

What I claim as new and wish to protect by Letters Patent is:

- 5 1. Process for the removal of sulfur compounds from mineral oil fractions which comprises contacting the same in an initial stage with an alkali metal plumbite solution under conditions to form lead mercaptides, separating the oil from the plumbite solution and distilling the same in the absence of steam and under vacuum at a temperature below 250° F. in a secondary stage under conditions to remove overhead a sweetened product.
  - 10 15. 2. Process as defined by claim 1 in which said oil boils in the motor fuel boiling range.
  - 20 3. Process as defined by claim 1 in which said oil passed to the initial stage has a final boiling point at least 5° F. above the final boiling point of the oil removed overhead in the secondary stage.
  - 25 4. Process for the removal of mercaptan compounds from petroleum oils containing the same which comprises contacting a petroleum oil in an initial stage with an excess of sodium plumbite solution under conditions to form basic lead mercaptides, separating the treated oil from the partially spent sodium plumbite solution and distilling the same in a secondary stage in the absence of steam and under vacuum at a temperature below 250° F. under conditions to remove overhead a distillate free of mercaptan compounds and to remove as a bottoms a relatively small quantity of higher boiling oil constituents containing dissolved therein the basic lead mercaptides, treating the bottom stream in a manner to remove the lead compounds therefrom, combining the lead compounds with said partially spent sodium plumbite solution and recycling the same to the system.
  - 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950
5. Process as defined by claim 1 in which said oil boils in the motor fuel boiling range.
  6. Process as defined by claim 4, in which the final boiling point of the feed oil to the initial stage is at least 5° F. higher than the final boiling point of the distillate removed overhead in said secondary stage.
  7. Process as defined by claim 4, in which the lead compounds are removed from the stream withdrawn from the bottom of said secondary stage by the addition of excess free sulfur.
  8. Process as defined by claim 4, in which the lead compounds are removed from the stream withdrawn from the bottom of said secondary stage by the addition of free sulfur controlled so that the oil withdrawn is substantially free of lead and contains no free sulfur.
  9. A process for the removal of sulfur compounds from mineral oil which comprises preparing a fraction having a substantially higher final boiling temperature than is desired in the finished oil, treating the fraction with an alkali metal plumbite solution in water to form lead mercaptides, separating the oil from the plumbite solution, and distilling from the plumbite-treated oil under vacuum and at a temperature below 250° F., a fraction having a final boiling point lower than that of the fraction first separated, to take overhead a substantially sulfur-free distillate and leave behind as bottoms a solution of mercaptides in heavy oil.
  10. A process for the removal of sulfur compounds from mineral oil which comprises preparing a fraction having a substantially higher final

boiling temperature than is desired in the finished oil, treating the fraction with an alkali metal plumbite solution in water to form lead mercaptides, separating the oil from the plumbite solution, and distilling from the plumbite-treated oil under conditions of reduced pressure and at a temperature below 250° F., a fraction having a final boiling point lower than that of the fraction first separated, to take overhead a substantially sulfur-free distillate and leaving behind as bottoms a solution of mercaptides in heavy oil.

11. A process for the removal of sulfur compounds from mineral oil which comprises preparing a fraction having a substantially higher final boiling temperature than is desired in the fin-

ished oil, treating the fraction with an alkali metal plumbite solution in water to form lead mercaptides, separating the oil from the plumbite solution, and distilling from the plumbite-treated oil under conditions of reduced pressure, freedom from water and temperatures below about 250° F. and below that at which serious decomposition of mercaptides occurs, a fraction having a final boiling point lower than that of the fraction first separated, to take overhead a substantially sulfur-free distillate and leave behind as bottoms a solution of mercaptides in heavy oil.

GEORGE R. GILBERT.
